(Continued)

Primary Examiner — Kelley Donnelly(74) *Attorney, Agent, or Firm* — Sheridan Ross P.C.(57) **CLAIM**

The ornamental design for a support apparatus, as shown and described.

DESCRIPTION

FIG. 1 is a front view of a support apparatus showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

The broken lines are for the purposes of illustrating the environment of the article only and form no part of the claimed design.
